G. C. HOSCH

SWIVELING SUPPORT

Filed March 31, 1919

Inventor:

Greene C. Hosch

by

Greene S. Elliott
his Atty.

UNITED STATES PATENT OFFICE.

GREENE C. HOSCH, OF ST. LOUIS, MISSOURI, ASSIGNOR TO THE MEASUREGRAPH COMPANY, OF ST. LOUIS, MISSOURI, A CORPORATION.

SWIVELING SUPPORT.

Application filed March 31, 1919. Serial No. 286,389.

To all whom it may concern:

Be it known that I, GREENE C. HOSCH, a citizen of the United States, residing in the city of St. Louis and State of Missouri, have 5 invented new and useful Improvements in Swiveling Supports, of which the following is a specification.

This invention relates to a swiveling support. While the device is intended to be 10 especially useful as a support for a counter accessory, such as a measuring machine, it may also be used to provide a swiveling support for a machine or device for any purpose.

15 The general object of the invention is to produce a swiveling support of very simple construction which is so constructed as to enable the device which it supports to rotate about an axis and which will operate 20 in such a way as to hold the device substantially fixed in a plurality of different positions; this result is accomplished by means operating automatically, that is to say by means which will operate simply by the rotation or swiveling movement without necessitating the direct manual operation of any locking member.

Further objects of the invention will appear hereinafter.

30 The invention consists in the general combination of parts set forth in the appended claims, and described in the following specification, all of which contribute to produce a simple and efficient swiveling support.

35 In the drawing which fully illustrates the preferred embodiment of my invention,

Figure 1 is a plan of the swiveling support, with dotted lines indicating the different positions which the rotary member of 40 the support may assume;

Figure 2 is a front elevation of the device with dotted lines indicating the different positions the rotary member may assume;

Figure 3 is a vertical section taken through 45 the device on the line 3—3 of Figure 1;

Figure 4 is a perspective showing a detail of the means for holding the rotary member in the different positions;

Figure 5 is a perspective showing further 50 details.

Referring more particularly to the parts, 1 represents a rotary member which is adapted to support any instrument or accessory, for example, a measuring instrument. Any suitable means may be provided for securing the instrument; for this purpose, at one side this rotary member or rotary head may be provided with a locking bolt 2 actuated by a suitable locking mechanism 2^a controlled by a suitable key. This bolt is 55 mounted so that it may project above the upper face of the head and thereby cooperate with three studs 3, to hold the instrument in place on the rotary member.

I provide means carried by the bracket 65 member 6 and the rotary member which will normally hold the rotary member 1 yielding against rotation but which will permit it to be rotated if a sufficient rotative force be applied to it. This is accomplished 70 by providing one of these members with a plurality of recesses disposed circumferentially around the axis of rotation and providing the other member with an interlocking projection. The projection and the recesses have inclined or curved engaging faces in order to co-operate so that when the projection is in one of the recesses, it will hold or detain the rotary member against 75 rotation, but will be disengaged automatically by the rotary, or swivel-movement.

In order to accomplish this and give the structure rigidity, the rotary member is pivotally mounted on a central stud 4, having an enlarged neck 5 at its middle portion, 85 the lower end of said stud being mounted in a tubular housing 7 which is formed integral with a bracket member 6.

The bracket member 6 may be in the form of a central post having an elongated shoe 90 6^a integral with it at its lower portion, and this shoe may be provided with suitable means for guiding it along the counter. For this purpose I provide a plate 8 carrying rollers or wheels 10 mounted on large pins 95 or studs 9 attached to the plate 8, (see Figure 3.) These wheels 10 operate as means for guiding the bracket member along a suitable track attached to the counter.

The stud 4 may be held in place by suit- 100

able nuts 12 mounted on its lower end, which seat against a washer 13 which lies against the lower end of the tubular housing 7.

I also provide means for yieldingly pressing the rotary member against the bracket member. For this purpose I prefer to provide the upper end of the bracket member 6 with a wear-plate 14 and on this wear-plate 14, there seats a corresponding wear-plate 15 carried by the underside of the rotary member 1. The rotary member is preferably formed with a chamber 1^a on its upper side, and in the bottom of this chamber, I secure socket means in the form of a socket-plate 16 which is secured to the rotary member by suitable screws 16^a. Seating on the socket-plate 16, I provide detent means 17 in the form of a collar which is secured to the stud 4 by means of a pin 18, said pin passing into a diametrically placed opening of the stud, through a vertical elongated slot 19 in the side of the collar. By reason of this slot it will be evident that an upward movement of the collar 17 on the stud will be permitted. The means for actually pressing the rotary member 1 yieldingly against the bracket member 6, consists of a spring-washer 20 which seats on the upper face of the collar 17, the same being held in place by a nut 21 which screws onto threads adjacent to the end of the stud. The socket-plate 16 is provided with a plurality of circumferentially disposed recesses which are in the form of radially disposed grooves 22. With these grooves 22, a projection 23 on the underside of the collar 17 co-operates. Normally the projection 23 engages one of these grooves 22, or two diametrically opposite grooves 22, in case the projection 23 lies on both sides of the axis of the collar 17, as in Figure 5. This holds or detains the rotary member against rotation. However, when it is desired to rotate the rotary member in its swiveling movement so as to hold it in a different position, it is simply necessary to rotate it forcibly. This rotation causes the socket-plate 16 to rotate under the collar 17 so that the projection 23 rides up on to the surface of the plate between the recesses. The yielding means 20 operates to yield, and this upward movement of the collar is permitted by the slot 19. The rotation is continued until the projection 23 comes opposite the next adjacent recesses whereupon the yielding means or spring-washer 20 will force the collar down and cause the projection 23 to engage the recesses, in this way locking or detaining the rotary member in a new position; in this way the recesses and the projection cooperate to hold the rotary head in a plurality of different positions.

Although I have illustrated only four of the recesses 22, which is all that would be required for the service stated, obviously there may be as many of these recesses as desired,

where advisable, to adapt the device to special purposes. In the present instance it has only been considered necessary to provide for holding the swiveling head in four different positions.

It is understood that the embodiment of the invention described above is only one of the embodiments my invention may take and I do not wish to be limited in the practice of the invention, nor in my claims to the particular embodiment set forth.

What I claim and desire to secure by Letters Patent is:

1. In a swiveling support, the combination of a relatively fixed bracket member having a post, a swivel-head supported on the upper end of the post, a pivot stud connecting the swivel-head and the post and rigidly secured to the post, a socket-plate attached to the swivel-head and having a plurality of recesses on the face thereof circumferentially disposed about the axis of the stud, a collar on said stud connected to the stud so as to rotate therewith and capable of a movement longitudinally on the stud, said collar having a projection seating on the said socket-plate to engage with any of the recesses to hold the rotary head against rotation, and a spring carried on the stud to force the collar against the socket-plate and permitting the collar to move away from the socket-plate when said head is given a swiveling movement.

2. In a swiveling support, the combination of a relatively fixed bracket member having a post, a swivel-head supported on the upper end of the post, having a chamber on its upper side, a pivot stud connecting the swivel-head and the post and rigidly secured to the post, a socket plate attached to the swivel-head in the bottom of said chamber and having a plurality of recesses on the face thereof circumferentially disposed about the axis of said stud, a collar on said stud connected to the stud so as to rotate therewith and capable of a limited upward movement on the stud, said collar having a projection seating on said socket-plate to engage with any of said recesses to hold said rotary head against rotation, and a spring above the collar and forcing the same down onto the socket-plate and permitting the collar to move upwardly when said head is given a swiveling movement.

3. In a swiveling support, the combination of a relatively fixed bracket member having a post, a swivel-head supported on the upper end of the post, having a chamber on its upper side, a pivot stud connecting the swivel-head and the post and rigidly secured to the post, a socket-plate attached to the swivel-head in the bottom of said chamber and having a plurality of recesses on the face thereof circumferentially disposed about the axis of said stud, a collar

on said stud connected to the stud so as to rotate therewith and capable of a limited upward movement on the stud, said collar having a projection seating on said socket-plate ⁵ to engage with any of said recesses to hold said rotary head against rotation, a spring above the collar and forcing the same down onto the socket-plate and permitting the col-

lar to move upwardly when said head is given a swiveling movement, and means carried on the upper face of the head for securing a counter accessory to the swivel head. ¹⁰

In testimony whereof, I have hereunto set my hand.

GREENE C. HOSCH.
